GARMENT BAG

Louis Marshall, Bronx, N.Y., assignor to General Utility
Bag Corporation, Jersey City, N.J.

Filed Mar. 13, 1970, Ser. No. 21,886

Term of patent 14 years

Int. Cl. D3—01

U.S. Cl. D87—5

FIG. 1 is a front elevational view of a garment bag showing my new design;

FIG. 2 is a side view thereof, the opposite side view thereof being identical thereto; and

FIG. 3 is a rear elevational view thereof.

I claim:

The ornamental design for a garment bag, as shown and described.
